UNITED STATES PATENT OFFICE.

GEORGE W. BERRIAN, OF LAKE CHARLES, LOUISIANA.

FLUID-FUEL BURNER.

1,192,735.

Specification of Letters Patent. Patented July 25, 1916.

Application filed September 21, 1914. Serial No. 862,802.

To all whom it may concern:

Be it known that I, GEORGE W. BERRIAN, a citizen of the United States, residing at Lake Charles, in the parish of Calcasieu and State of Louisiana, have invented certain new and useful Improvements in Fluid-Fuel Burners, of which the following is a specification.

This invention relates to improvements in fluid fuel burners and more particularly to such as are adapted for burning kerosene or other heavy hydrocarbon fuel oils.

An object in view is the production of a burner applicable to the firebox of an ordinary range or other like fire box, the parts being disposed to be readily accessible.

A further object is facilitating, by a simple means, the action of flaming gas in the heating of the retort portion of the oil supply pipe for insuring effective gasification prior to discharge of the fuel toward the point of consumption.

With this and other objects in view, the invention comprises a base adapted for application to a fire-box, and a supply pipe extending across the base to form a retort and sustained on the base and having a discharge pipe communicating with the retort and extending along the base, air mixing casings upstanding from and communicating through the base and inclosing the discharge portions of said discharge pipe, and deflecting surfaces overhanging the casings and disposed for receiving the impact of discharge from said discharge pipe.

The invention comprises certain other novel combinations, and arrangements of parts as will be hereinafter specified and claimed.

In the accompanying drawing: Figure 1 is a longitudinal vertical central section, part being seen in elevation and parts being broken away, Fig. 2 is a transverse vertical section taken on the plane indicated by line 2-2 of Fig. 1 and looking in a direction indicated by the arrow.

Referring to the drawing by numerals, 1 indicates a base which is adapted to be applied in the fire box of the range or other like fire box, the walls of which are indicated at 2, and the intervening space between the walls and the base 1 is filled with asbestos or other fire proof substance 3 adapted to prevent the entrance of air from beneath the base into the space above the base except through the mixers hereinafter mentioned.

Upstanding from and preferably formed integral with base 1 and spaced apart longitudinally thereof are tubular frusto-conical air mixers 4-4. A fuel supply pipe 5 extends longitudinally of the base 1 and through suitable openings in the mixers 4, the pipe at its inner end being bent upwardly and then extended forwardly to form a retort portion 6 which at its outer end connects with a proper supply pipe 7 adapted to deliver the fluid fuel. The retort portion 6 extends in a line directly above pipe 5, as clearly seen in Fig. 2, and immediately above each of the mixers 4, pipe 6 carries a deflector plate 7. Each plate 7 is preferably formed with a ring or band 8 surrounding the pipe 6 and detachably secured in place thereon as by set screw 9 threaded through the ring and engaging the pipe. Bracket 10 is fixed to base 1, at one side thereof, and extends upwardly and is bent laterally to engage retort 6 for supporting the same, the upper end portion of the bracket being bifurcated for receiving the pipe and in which bifurcation the retort 6 rests. The outer end of pipe 5 is provided with a cap 11 adapted to engage the outer mixer 4 when the pipe is at its innermost position, the pipe being shiftable longitudinally, as indicated by the dotted line position in Fig. 1 so that the discharge apertures 12 formed in pipe 5 and normally disposed approximately central of mixers 4 may be moved to a position outside of said mixers for enabling the discharge of fuel onto the base 1. It is to be noted that the shiftable pipe 5 fits snugly in the lateral openings of the mixer casings and constitutes closures for said openings so as to prevent the ingress of air therethrough in the use of the device, thereby insuring that the proper combustion will take place upon passage of air vertically through said casings. This is a very essential feature of my device. Base 1 is formed with depressions or fire pans 13 for receiving such fuel, the pans being adapted to be supplied with fuel for enabling starting of the burner. The apertures 12 direct their discharge upwardly normally against the baffle plates 7, and in starting the burner the retort 6 and pipe 5 are drawn outwardly to the dotted line position when the fuel supply is turned on. As soon as the pans 13 are substantially filled the supply is cut off and the pipes are shifted back to their inner position and the

fuel in the pan 13 is lighted and allowed to burn up for heating the pipes 5 and 6. Thereupon the fuel supply is again turned on and the gas created by the heat of the pipes discharges through apertures 12 and it is ignited. Baffles 7 deflect the flame and cause it to spread so as to substantially fill the surrounding fire box. The jet from each aperture 12 acts as an injector for drawing in air through the receptive mixer 4 so that the combustible mixture is delivered from each of the mixers 4 continuously during operation. When it is desired to reduce the intensity of the heat the fuel supply is cut down and the air supply may be proportionately cut down by closing the doors of the range and preventing the intake of the air beneath the base 1, or the doors or slides may be only partially closed, the adjustment of the parts being proportionate to the quantity of air required, a greater amount of air being admitted beneath the base 1 as the amount of fuel supplied is increased.

Having thus described the invention, what I claim as new is:—

The combination with an inclosure, of a fuel burner disposed therein and comprising

a horizontal base plate so arranged in the inclosure as to prevent passage of air about the edges of the plate, an air mixing casing upstanding from the plate and providing an opening therethrough, the material of the base plate being depressed below its horizontal plane in a relatively restricted area adjacent to the casing to form a starting fuel pan, said casing having diametrically opposite apertures at its lowermost portion adjacent to the surface of the plate, and a fuel supply pipe extending laterally through the apertures of the casing over the starting pan and having a discharge opening adapted in operation to direct the discharge through the casing, the supply pipe snugly fitting in said casing apertures and constituting a closure therefor whereby to prevent passage of air through said openings.

In testimony whereof I affix my signature in presence of two witnesses.

GEORGE W. BERRIAN.
